[57] **ABSTRACT**

Device for monitoring the relative position of synchronously moved control elements, especially for monitoring the movement of two valve cases in safety valves controlling a pneumatic or hydraulic drive. The device includes a magnetic member disposed at each of the valve cases and symmetrically arranged with respect to one another, a rotatably mounted magnetic bar having each of the magnetic members arranged proximate to a free end thereof for magnetically influencing the positioning thereof. Spring forces and magnetic forces are effective on the bar so as to provide the bar with a first basic stable position corresponding to synchronous movement of the valve cases and two stable disturbance positions corresponding to asynchronous movement of the valve cases.

DEVICE FOR MONITORING CONTROL ELEMENTS

The present invention relates to a device for the monitoring of the relative position of synchronously moved control elements, in particular for the monitoring of the movement of two valve cases in safety valves for the control of pneumatic or hydraulic drives.

Many different types of constructions of monitoring devices for safety valves are known. Thus, there are arrangements, for example, wherein a mechanical coupling of the two valve cases is provided with the aid of a thin wire attached to extensions on the valve cases, the wire having current flowing therethrough and ruptures in case of an asynchronous movement, thus interrupting the monitoring circuit. However, such monitoring devices have the disadvantage that a new safety wire must be installed in each case in order to return the mechanism into the operative condition, which is very time-consuming and cumbersome and unnecessarily prolongs the time for placing the device or monitored equipment back into operation, even though the actual error had been found very quickly.

Another known mechanical solution (French Pat. No. 1,292,283) disposes a cross member between the two valve stems, in place of a safety wire, with a plunger being displaceably arranged in the cross member. The plunger, on the one hand, is in engagement with an electrical switching contact and, on the other hand, via an interposed ball, contacts a groove of a valve stem, so that it is displaced in case of a nonuniform operation of the valve stems and can cut off the drive via the switching contact. This solution has the disadvantage of being extremely trouble-prone, since the plunger can easily jam. Also, the response accuracy is relatively low, due to the selected mechanical tripping arrangement.

Other mechanical monitoring mechanisms have been proposed (DAS Pat. No. 1,294,818) wherein the free ends of the valve stems contact a rocker plate via springs such that the position of this plate remains unaffected during ordinary operation, with the plate being pivoted only in case of an asynchronous operation of the valve stems and triggering a switching contact via a cam disposed in the center thereof. In this arrangement, the response accuracy as in the other monitoring devices is also not very high. In particular, difficulties are to be expected in the monitoring safety, because the two springs utilized exhibit aging phenomena, primarily after a longer operating period due to the constant stress, resulting in erroneous indication of disturbances. Additionally, there is the difficulty of being able to adapt the characteristics of both springs to each other in such a manner that the forces exerted by the valve stems on the rocker plate at each stroke are always equally large.

It has also been known to effect the monitoring of the synchronous movement by means of a pneumatic coupling, in such a manner that a control pressure for placing the valve cases into the operating position is reduced in case of an asynchronous operation of the valve cases, so that the further operation of, for example, a hydraulic or pneumatic press is interrupted (DAS Pat. No. 1,249,040). Devices of this type can be quickly returned to service by an appropriate structure. However, it has been found that disturbances in the control pressure can result, during the course of time,

in impairing the safe operation of the monitoring device in some instances, thus leading to interruptions of the operation even if there is no actual flaw in the valve system proper.

Therefore, it is an object of the present invention to avoid the disadvantages of the prior art devices and to provide a monitoring device which is maximally simple and service-free and yet has the properties to effect an interruption of the operation in case an error occurs and a quick return to operation after the flaw has been located.

The present invention provides a monitoring device having an element consisting of a magnetic material fixedly attached to each valve case, these elements being arranged in symmetry to each other. Each element is disposed in the zone of the free ends of a rotatably mounted magnetic bar for magnetically influencing the bar. The magnetic bar is adjusted, in its basic position, to the synchronous position of the valve cases and triggers a signal for the inactivation of the drive upon rotation out of the basic position. This arrangement makes it possible to provide that, when the two valve cases are operating synchronously, the magnetic forces exerted on the magnetic bar at both ends are respectively equally large, so that the position of the magnetic bar remains unaffected. In contradistinction, when the operation is asynchronous, the magnetic bar is moved out of its basic position, and this deflected motion of the magnetic bar can be utilized for triggering a pulse for error indication and, for example, also for shutting off the control valve and thus render a press inoperative. The novel monitoring device can be constructed without wear-prone parts and thus is service-free to an unlimited extent. Additionally, the device can be designed to be relatively simple and thus inexpensive.

According to a feature of the present invention, the magnetic bar is maintained in its basic position by means of spring force, so that the monitoring device becomes independent of location. In order to provide large magnetic forces in a maximally simple manner, the magnetic bar can consist of soft iron and can be disposed in a magnetic member which annularly surrounds the magnetic bar. This magnetic member can be, for example, an electromagnetic coil. However, in an especially simple manner, a permanent magnet is provided as the magnetic member and is fashioned as an annular closed soft-iron bridge member. According to another feature of the invention, a torsion rod is arranged for the monitoring of the magnetic bar so that wear of the parts due to friction does not occur.

In accordance with a further feature of the present invention, to provide for the triggering of an error-detection pulse, the magnetic bar is arranged to engage plungers on both sides of its fulcrum, which plungers are connected to electric switches. Each rotational deflection of the bar thus triggers a switching process. In this connection, it is especially advantageous to adapt the spring force of the torsion rod to the magnetic forces in such a manner that the magnetic bar has a basic stable position determined by the spring force and two disturbance positions determined by the magnetic forces from which disturbance positions the magnetic bar can be returned into the basic position only by a separate switching step. This arrangement fulfills the prerequisite that, in case of a disturbance, the valve cannot be returned to operation until a separate switch-

ing process is triggered after elimination of the trouble. In this connection, it has been found that, due to the square force characteristics of the magnetic forces, two changeover points result in the movement of the magnetic bar from which the stable basic position into the respective disturbance positions, which are again stable, and that, because of this property, the magnetic bar is deflected, after passing the changeover points, suddenly, rather than gradually, so that high-power limit switches can be connected to the actuating plungers. The provision of microswitches and the additional arrangement of heavy-duty switches are thus eliminated. Finally, in safety valves having electromagnetically operated auxiliary control valves for the valve cases, provision can be made for restoring the magnetic bar into the basic position by arranging a short-circuiting switch bridging the electrical switches in contact with the plungers and being located in the circuit of the auxiliary valves. This short-circuiting switch, upon its actuation, serves for placing both valve cases into a synchronous position and thus effects a restoration of the magnetic bar into the basic position by the thus-produced predominance of the restoring spring forces.

These and further objects, features and advantages of the present invention will become more obvious from the following description when taken in connection with the accompanying drawings which show, for purposes of illustration only, several embodiments in accordance with the present invention, and wherein

FIG. 1 is a schematic cross-sectional view through a safety valve having a monitoring device according to the present invention;

FIG. 2 is an enlarged partial cross-sectional view of the monitoring device in the basic operating position, wherein the left-hand and right-hand halves of the figure illustrate different possibilities for the construction of the magnetic bar;

FIG. 3 shows the monitoring device of FIG. 2 in the disturbance position; and

FIG. 4 is a diagram representing the force relationship at the magnetic bar of the monitoring device.

Referring now to the drawing wherein like reference numerals designate like parts throughout the several views, there is shown in FIG. 1, two valve cases 2 and 3 disposed within the housing 1 of a safety valve. Each valve case comprises a valve stem 2a and 3a respectively, a valve element 4 having the shape of a piston, and a disk valve member 5 attached to the valve stem. The valve cases 2 and 3 are arranged within the housing 1 in such a manner that they respectively close or uncover valve seats 6 and 7 during their upward and downward movement. The valve seats connect an upper pressure medium chamber 8 and a lower pressure medium chamber 9 with each other; the chambers being charged with the pressure medium in a conventional manner not illustrated in detail.

In the illustrated position, the valve disks 5 respectively seal the lower valve seat 7, so that the communication between the chambers 8 and 9 is interrupted. When introducing pressure medium into the space 10 respectively located above each of the pistons 4, the valve cases 2 and 3 move downwardly such that the disks 5 free the valve seats and the pressure chambers 8 and 9 are placed in communication with each other. The feed and discharge ducts of the pressure medium into and out of the chambers 8 and 9 are provided in

the conventional manner and therefore are not shown. The pressure medium passes into the spaces 10 above the pistons 4 via auxiliary control valves 11 which are controlled electromagnetically and are connected in a circuit 12 wherein two switches 13 are disposed as will be discussed below.

Valves of the illustrated type are utilized, for example, for the control of hydraulic presses where a flawless functioning of the valve is important, for example 10 in order to exclude injury to the operating personnel. For this purpose, the two valve cases 2 and 3 are connected in parallel, so that even if one valve case should become inoperative due to a flaw, the faultless functioning of the safety valve is still ensured. A 15 prerequisite therefor is that the valve cases 2 and 3 are each moved synchronously and, in case this synchronous movement is absent, a disturbance signal is triggered which controls the machine connected thereto, for example the hydraulic press, to render the same inoperative. In accordance with safety regulations, it 20 must be ensured that the press can be placed back into operation only after the flaw at the valve or also at the feed line thereto has been repaired.

In order to monitor the synchronous operation of the valve cases 2 and 3, a monitoring device 14 is provided which comprises a magnetic bar 16 mounted at a torsion rod 15 and a permanent magnet fashioned as a soft-iron bridge 17. The permanent magnet, as can be seen particularly from FIG. 2 is provided with apertures 30 18 with extensions 19 of the valve stems 2a and 3a extending into these apertures, the extensions being made of a magnetic material. The magnetic bar 16 can have a configuration, as shown in the left-hand portion of FIG. 2, such that the extensions 19 sweep past the ends thereof. Alternatively, as illustrated in the right-hand portion, the magnetic bar can also be provided with bores 16a at both of its ends such that the extensions 19 enter these bores and can thus exert a stronger magnetic effect. The magnetic bar 16 is held in its basic 35 position shown in FIG. 2 by the spring force of the torsion rod 15, on the one hand, and also by the two plungers 20, on the other hand, under the biasing effect of the springs 21 which press the plungers 20 against the magnetic bar 16 and keep the switches 13, mentioned above, in the closed position.

During synchronous operation of the safety valve, the position of the magnetic bar 16 according to FIG. 2 remains unchanged because the forces exerted on the magnetic bar by the permanent magnet 17 and the extensions 19 moved therein are equally large at both ends of the bar 16. The switches 13 therefore remain closed, and the spaces 10 (FIG. 1) can each be charged with the pressure medium in a controlled rhythm.

In case an error or disturbance occurs such that the valve cases 2 and 3 do not move in synchronism, the left extension 19, for example, will be shifted at the stem 2a farther downwardly than the right extension 19 of the stem 3a, as illustrated in FIG. 3. Due to this asymmetry, the magnetic flux at the left end of the magnetic bar 16 is larger than the magnetic flux at the right end of the magnetic bar 16 such that a force is effective on the magnetic bar 16 in the direction of arrow 21, and the magnetic bar is rotated by the angle ϕ from its basic position into the disturbance position according to FIG. 3. The manner in which this rotation takes place and the effects of the forces are described in detail hereinbelow with reference to FIG. 4. As shown in

FIG. 3, by the rotation of the magnetic bar 16, the right-hand plunger 20 is pressed downwardly, so that the right-hand switch in FIG. 1 is opened and interrupts the circuit to the auxiliary valves 11. This interrupts the feed of pressure medium to the spaces 10, and both valve cases 2 and 3 return into their initial position shown in FIG. 1, wherein there is no communication between chambers 8 and 9. In this position, no operating pressure medium flows from the valve to the machine connected thereto, i.e., no pressure medium is fed to the press cylinder such that the press ram would likewise return into the initial position.

The safety valve as well as the press ram remain in the initial position until the flaw has been corrected and the two valve cases 2 and 3 have returned into their synchronous position and/or the magnetic bar has been returned to its basic position as shown in FIG. 2. The resetting, in case of valves of the type shown in FIG. 1, i.e., in case of valves having electromagnetically controlled auxiliary valves, can be effected in a very simple manner by providing an additional switch 22 as shown in FIG. 1 disposed in a short-circuit branch line 23 connected to the circuit 12 and bridging the two switches 13.

After having explained the mode of operation of the monitoring device of the present invention in its basic aspects, a detailed discussion of the switching procedure involving the magnetic bar 16 will now be provided with reference to FIG. 4. In FIG. 4, the axis K_{16} is used for plotting the forces effective on the magnetic bar 16, which latter acts as a type of armature in the magnetic system. Among the forces effective on the magnetic bar 16, there are first of all the spring forces denoted by f , which are shown as a full line and which linearly increase with increasing twisting angle ϕ . These spring forces are composed, in the illustrated example, of the spring force of the torsion rod 15 and of the forces of the springs 21 effective on the magnetic bar. The magnetic forces m , shown in dot-dash lines and having a square force characteristic, act in opposition to the spring forces. It can be seen from the diagram that the spring forces f effective oppositely to the magnetic forces m are still larger, within a certain twisting angle ϕ , than the magnetic forces m , and the curve $f-m$ passes through zero in a point P_k , wherein the difference of the spring forces and the magnetic forces is zero, and from this point, with increasing ϕ , the magnetic forces greatly increase. Thus, the rotational movement of the magnetic bar 16 up to the changeover point P_k is within a tolerance range for the maximally permissible deviation from the synchronous movement, but that thereafter a sudden rotational movement is effected. As such, rather than utilize microswitches for the switches 13, simpler heavy-duty switches can be employed.

On the basis of these force relationships, the magnetic bar 16 is provided with one stable basic position g , namely for all angles of rotation between the two changeover points P_k , and with two stable disturbance positions in the ranges s between the angle at the changeover point P_k and the respectively external abutment position. Consequently, the device of the present invention makes it possible with a corresponding dimensioning of the springs and the torsion rod 15 and an appropriate design of the magnetic forces, to eliminate the need for complicated sensing and scanning elements, or the arrangement of special, sensitive

switches, since the construction of the present invention is excellently suitable, in spite of its sensitive monitoring action, for delivering mechanical forces readily sufficient for the operation of heavy-duty switches. By the provision of means for lessening the spring force instead of the torsion rod 15, or by making the springs 21 adjustable, it is also possible to render the changeover point of the monitoring device adjustable. This, then, also affords a possibility for adjusting the permissible deviation of the valve stem positions.

Obviously, many modifications and variations of the present invention are possible in the light of the above teachings. It should therefore be understood that within the scope of the appended claims, the invention may be practiced otherwise than as specifically described.

I claim:

1. Device for monitoring the relative position of two movable elements arranged for corresponding synchronous movement, said device comprising a first magnetic member arranged on each of said movable elements and symmetrically disposed with respect to one another, magnetic bar means mounted for rotational movement and having a respective one of said first magnetic members arranged proximate to a respective free end thereof for magnetically influencing the positioning of said magnetic bar means, said magnetic bar means having a first basic position corresponding to the synchronous positioning of said movable elements and being rotatable from the first basic position in response to asynchronous movement of said movable elements, and means responsive to the movement of said magnetic bar means for providing an indication of the asynchronous movement of said movable elements.

2. A monitoring device according to claim 1, further comprising spring force means for biasing said magnetic bar means into the first basic position thereof.

3. A monitoring device according to claim 1, wherein said magnetic bar means is a soft iron bar and a second magnetic member annularly surrounds said magnetic bar means, said magnetic bar means being disposed within said second magnetic member.

4. A monitoring device according to claim 3, wherein said second magnetic member is a permanent magnet and is constructed as an annular closed soft iron bridge member.

5. A monitoring device according to claim 1, further comprising torsion rod means for rotatably mounting said magnetic bar means.

6. A monitoring device according to claim 1, wherein said means responsive to the movement of said magnetic bar means comprises means for providing an output signal indicative of such movement including plunger means arranged for contacting said magnetic bar means proximate to each end thereof and switch means arranged in an electrical circuit means, said switch means being responsive to the movement of said plunger means for triggering an output signal in said circuit means.

7. A monitoring device according to claim 2, wherein said magnetic bar means is positioned in accordance with the magnetic forces and spring forces effective thereon, said spring force means providing spring forces coordinated with the magnetic forces so as to provide the first basic stable position of said magnetic bar means corresponding to synchronous positioning of said movable elements within predetermined limits, and the magnetic forces effective on said magnetic bar

means overcoming the spring forces in response to asynchronous movement of said movable elements to provide two disturbance stable positions for said magnetic bar means.

8. A monitoring device according to claim 7, further comprising switching means effective for returning said magnetic bar means from one of the stable disturbance positions to the first basic stable positions thereof.

9. A monitoring device according to claim 7, wherein said magnetic bar means is only responsive to switching means effective for returning said magnetic bar means from one of the stable disturbance positions to the first basic stable position thereof.

10. A monitoring device according to claim 1, wherein said two movable elements are two valve means of a safety valve for controlling one of a pneumatic or hydraulic drive.

11. A monitoring device according to claim 10, wherein said two valve means each include a movable valve stem means and said first magnetic member is fixedly arranged on said valve stem and extends therefrom.

12. A monitoring device according to claim 11, wherein said magnetic bar means is provided with an aperture means approximate to each free end thereof, and said aperture means is arranged for receiving one of said first magnetic members extending from said valve stem means.

13. A monitoring device according to claim 11, wherein said means for indicating the asynchronous movement of said movable elements includes means for triggering a signal for shutting off the drive which is controlled.

14. A monitoring device according to claim 13, wherein said means for triggering a signal include plunger means arranged for contacting said magnetic bar means proximate to each end thereof and switch means arranged in a circuit and being responsive to the movement of said plunger means for triggering a signal when said magnetic bar means moves from the first basic position thereof.

15. A monitoring device according to claim 10, further comprising spring force means for biasing said magnetic bar means into the basic position thereof.

16. A monitoring device according to claim 15, wherein said magnetic bar means is a soft iron bar and a second magnetic member annularly surrounds said bar, said bar being disposed within said second magnetic member.

17. A monitoring device according to claim 16, wherein said second magnetic member is a permanent

magnet and is constructed as an annular closed, soft iron bridge member.

18. A monitoring device according to claim 17, wherein said permanent magnet is provided with a plurality of aperture means and said first magnetic members extending from said valve means extend through respective ones of said aperture means into the region proximate to the free ends of said magnetic bar means.

19. A monitoring device according to claim 10, further comprising torsion rod means for rotatably mounting said magnetic bar means.

20. A monitoring device according to claim 11, wherein said means for providing an indication of the asynchronous movement of said movable elements comprises means for triggering a signal for shutting off the drive which is controlled and includes plunger means arranged for contacting said magnetic bar means proximate to each end thereof, and switch means arranged in a circuit means and responsive to the movement of said plunger means, said plunger means actuating said switch means in response to movement of said magnetic bar means from the basic position thereof.

21. A monitoring device according to claim 20, wherein said magnetic bar means is positioned in accordance with the magnetic forces and spring forces effective thereon, said spring force means providing spring forces coordinated with the magnetic forces so as to provide the first basic stable position of said magnetic bar means corresponding to synchronous positioning of said valve means within predetermined limits, and the magnetic forces effective on said magnetic bar means overcoming the spring forces in response to asynchronous movement of said valve means to provide two stable disturbance positions for said magnetic bar means.

22. A monitoring device according to claim 21, further comprising switching means effective for returning said magnetic bar means from one of the stable disturbance positions thereof to the first basic stable position thereof.

23. A monitoring device according to claim 22, further comprising electromagnetically actuated auxiliary control valve means for said valve means, and said switching means for returning said magnetic bar means to the first basic stable position thereof includes a short-circuit switch means for bridging said switch means responsive to said plungers and arranged in the circuit means of said auxiliary control valve means.
